UNITED STATES PATENT OFFICE.

JAMES A. O'NEILL, OF SPRINGFIELD, MASSACHUSETTS.

METHOD OF MAKING IMITATION MARQUETRY, PARQUETRY, INLAYS, ETC.

Application filed October 22, 1927. Serial No. 228,017.

This invention relates to a method of making imitation marquetry, parquetry, inlays, etc. in wood or manufactured resemblance of natural wood.

5 The primary object of this invention is to obtain on a single surface the effect or appearance of several sections having various grains of varieties and species of the same or different woods, with these separate sections of the surface colored or stained in such manner as to prevent the color or stain in any single section from creeping into or entering and discoloring any portion of bordering or surrounding sections so that the completed product will have the effect or appearance 10 of variously grained, colored or stained sections with clear and distinct bordering and surrounding lines and the imitation will have the same effect or appearance as if it 15 were the real article.

I am aware that attempts have been made heretofore of an analogous nature but the imitations of the wood grain effects or appearances were more or less imperfect because it has heretofore been impossible to produce in the surface good resemblances of 20 wood grain effects or appearances that were not removed, altered or distorted by stain or other coloring material or by finishing 25 material subsequently applied.

I am also aware that attempts have previously been made to color or stain a single surface of wood or manufactured resemblance of natural wood in varying color effects or appearances; but the designs have been more or less imperfect because it has heretofore been impossible to produce in a 30 single surface the effect or appearance of various separate sections with clear, sharp, fine and distinct lines of division or demarcation, coated and insulated in such a manner as to prevent the stain or coloring material in any single section from creeping into and discoloring portions of bordering or 35 surrounding sections; thus spoiling or distorting the design.

In the accompanying drawings—

Figure 1 is a plan view showing a block or panel with a design thereon made in accordance with my improved method;

Figures 2 and 3 are exaggerated views in section on the line 2—2 of Figure 1, illustrating different steps in the carrying out of the method.

55 A block, panel or other article such as illus-

trated at 1 may be formed in any way desired either as a solid member or as made up in sections, but of course it is understood that my invention will apply to any article or surface decoration where wood or manufactured resemblance of natural wood is employed.

If necessary the surface of the wood or manufactured resemblance of natural wood is smoothed by planes, sandpaper, scraper or other means employed.

Then the surface is burned, scorched, branded or seared by flames through stencils or by heated dies such as engravings, photo-engravings, electrotypes, stereotypes or casts of same, or other heated implements or by acids or other caustic chemicals, in designs or patterns to closely imitate the varying surface effects or appearances of the grains of as many varieties or species of the same 75 or different natural woods as desired. At the same time and by the same means thin, fine lines 2 of division or demarcation are burned, scorched, branded or seared on and through the surface to give the effect or appearance of as many separate and distinct 80 parts, sections or pieces of different or various woods as desired.

This burning, scorching, branding or searing of the surface obscures or tends to obscure 85 the original grain of the wood or surface markings of the wood or manufactured resemblance of natural wood. Thus producing an entirely new and different surface effect or appearance as desired. It also leaves an indelible impression of wood grain effects or 90 appearances that is not removed, altered or distorted by the coloring, staining or finishing materials to be applied later.

In carrying out my improved method, I 95 outline the design by a scored line or lines 2. The scored line or lines are formed by a sharp or pointed implement, or preferably by needle, as it is difficult, if not impossible, to employ a blade of any appreciable width 100 which will not follow the grain of the wood. These scored lines leave grooves of an appreciable depth in the wood.

The next step is to employ a coating 3, such as shellac and other analogous material, in 105 the grooves or scored lines 2 and over the surface of the wood a desired distance. This coating 3 acts as an insulator to prevent the stain or other coloring material 4 applied to the design from running past the scored lines, 110

so that the design is clear cut, and furthermore the scored lines give the impression of separate pieces.

The space between the design elements can be colored or left uncolored and the surface may be grained or finished in any way desired.

It will therefore be noted that the broad idea of my invention is the provision of a scored line or groove constituting the outline of a design, the wall of which is coated so as to prevent the creeping of stain or coloring matter across the line.

I, therefore, by reason of my improved method create a design which is clear cut and which has the same appearance as if the article were made according to the art to which it belongs.

I claim:

20 1. A method of the character described, including the formation of a groove or scored line extending across the grain of the wood in outlining a design, then coating a wall of the groove or scored line with a material 25 which will prevent the passage therethrough

of stain or coloring matter, and then coloring the design.

2. The herein described method of making imitation articles in the art of marquetry, parquetry, inlays, etc., including the provision of an article of wood, then forming a design in the surface of the wood by a scored line or groove, next coating a wall of the groove and a portion of the surface of the wood with a coating constituting an insulation against the passage of stain or other coloring matter, then depositing the coloring matter on the surface of the wood to form a design, and then finishing the surface of the wood.

3. A method of the character described, including the formation of a grooved design in the surface of a piece of wood, coating a wall of said groove to prevent the passage of stain from one portion of the design to another, graining the surface of the wood between the lines of the design, and finishing the surface of the complete design with transparent material.

JAMES A. O'NEILL.
